(57) **CLAIM**

The ornamental design for a switch plate, as shown and described.

DESCRIPTION

FIG. 1 is a perspective view of a switch plate according to the present invention.

FIG. 2 is a front view of the switch plate of FIG. 1.

FIG. 3 is a top view of the switch plate of FIG. 1; and, FIG. 4 is a side view of the switch plate of FIG. 1. The opposite side view is identical thereto.

The rear of the switch plate of FIG. 1 forms no part of the claimed design. The dashed lines shown in the drawings illustrate portions of the switch plate that are not presently claimed and thus form no part of the claimed design.
